UNITED STATES PATENT OFFICE.

JOHN SODERQUIST, OF BELOIT, WISCONSIN.

FLUE-CLEANER.

1,390,831.

Specification of Letters Patent. Patented Sept. 13, 1921.

Application filed July 29, 1920. Serial No. 399,794.

To all whom it may concern:

Be it known that I, JOHN SODERQUIST, a citizen of the United States, residing at Beloit, in the county of Rock and State of Wisconsin, have invented certain new and useful Improvements in a Flue-Cleaner, of which the following is a specification.

This invention relates to flue cleaners, and has for one of its objects to produce a simply 10 constructed device of this character whereby a soot removing plate is swingingly mounted on a turning rod with means for setting the plate substantially in parallel relation to the rod to enable it to be passed edge-wise through a flue in one direction and then 15 disposed at right angles to the rod or cross-wise of the flue by partly rotating the rod, for passage in soot removing position in the opposite direction through the flue.

20 With these and other objects in view, the invention consists in certain novel features of construction as hereinafter shown and described, and then specifically pointed out in the claims, and in the drawings illustrative 25 of the preferred embodiment of the invention.

Figure 1 is a view of the plate from one side arranged for passage of the plate edge-wise through a flue.

30 Fig. 2 is a view of the plate from the opposite side with the parts arranged as in Fig. 1.

Fig. 3 is a section on the line 3—3 of Fig. 1.

35 Fig. 4 is a plan view with the parts arranged as in Fig. 1.

Fig. 5 is a view similar to Fig. 1, with the parts arranged for passage of the plate crosswise through the flue.

40 Fig. 6 is a view of the plate with the parts arranged as in Fig. 5.

Fig. 7 is a plan view with the parts arranged as in Fig. 5.

45 Fig. 8 is a detached perspective view of a portion of the main operating rod.

The improved device comprises a metal plate 10 preferably oblong with curved ends, the curvatures corresponding to the interior curvature of the flue to be cleared of soot 50 and other obstructions.

The implement may be constructed of plates of varied sizes, as will be obvious.

A turning and operating rod 11 is mounted 55 for rotation through the plate and is provided with a turning handle 12, as shown.

Attached to the plate 10 at one side are

bearings 13, and mounted for rotation at one end in the bearings are brace rods 14, the latter engaging the rod 11 by collars 15, and the collars being spaced from the plate. 60

Attached by its ends at 16 to opposite side of the plate 10 is a keeper rod 17, preferably curved concentrically to the rod 11. The rod 11 is bent at right angles to form an arm 18 which extends at its free end between the keeper 17 and the plate. 65

At the juncture of the arm 17 and the body of the operating rod 11, the latter is reversely bent as represented at 19, the reverse bend being curved, as shown. 70

By this arrangement the plate 10 can be rolled over on the short curved reverse bend to dispose the plate substantially in parallel relation to the longitudinal axis of the rod with the arm 18 presented downwardly or at 75 one end of its path within the keeper 17, as shown in Figs. 1 and 2.

In this position the plate can be passed edge-wise through a flue a portion of which is represented at 20 with a section of the flue 80 sheets at 21 and 22, in one direction so as to disturb or move the soot or ashes as little as possible, and then by simply rotating the rod about one fourth of a revolution, the arm 18 will travel beneath the keeper 17, 85 and cause the short curved reverse bend 19 to roll through the aperture and turn the plate 10 at right angles to the rod, so that when the rod is moved in the opposite direction, the plate will pass through the flue 90 crosswise thereof, and draw the soot and ashes therewith.

The improved device is simple in construction, can be inexpensively manufactured and of any required size to adapt it to various 95 sizes of flues.

The preferred embodiment of the invention is disclosed in the drawings and set forth in the specification, but it will be understood that any modifications within the 100 scope of the claims may be made in the construction without departing from the principle of the invention or sacrificing any of its advantages.

I claim:

1. In a flue cleaner, a plate having a keeper secured thereto and in parallel relation therewith, and a turning rod passing through said plate and rotative through the plate and coupled therewith and having a 110 right angled projection movable between the keeper and plate, said rod having a reverse

- bend at the juncture of the rod and the projection thereof, whereby the plate may be disposed substantially parallel to the longitudinal axis of the rod for passage in one direction through a flue and disposed at right angles to the rod by partially rotating the same for moving the plate in the opposite direction through the flue.
2. In a flue cleaner, a plate having a keeper secured thereto and in parallel relation therewith, a turning rod passing through said plate and having a right angled projection movable between the keeper and plate, said rod having a reverse bend at the juncture of the rod and the projection there-

of, and means for swingingly coupling the plate to the rod.

3. In a flue cleaner, a plate having a keeper secured thereto and in parallel relation therewith, a turning rod passing 20 through said plate and having a right angled projection movable between the keeper and plate, said rod having a reverse bend at the juncture of the rod and the projection thereof, and bracket devices pivotally connected 25 to the plate and to the rod.

In testimony whereof, I affix my signature hereto.

JOHN SODERQUIST.
